[57] CLAIM

The ornamental design for ultrasonic probe, as shown and described.

DESCRIPTION

FIG. 1 is a top, front, and right side perspective view of a ultrasonic probe showing my new design;

FIG. 2 is a front elevational view;

FIG. 3 is a top plan view;

FIG. 4 is a right side elevational view;

FIG. 5 is a left side elevational view;

FIG. 6 is a rear elevational view;

FIG. 7 is a top, front and right side perspective view of a first embodiment of FIGS. 1-6;

FIG. 8 is a front elevational view;

FIG. 9 is a top plan view;

FIG. 10 is a right side elevational view;

FIG. 11 is a left side elevational view;

FIG. 12 is a rear elevational view;

FIG. 13 is a top, front and right side perspective view of a second embodiment of FIGS. 1-6;

FIG. 14 is a front elevational view;

FIG. 15 is a top plan view;

FIG. 16 is a right side elevational view;

FIG. 17 is a left side elevational view;

FIG. 18 is a rear elevational view;

FIG. 19 is a top, front and right side perspective view of a third embodiment of FIGS. 1-6;

FIG. 20 is a front elevational view;

FIG. 21 is a top plan view;

FIG. 22 is a right side elevational view;

FIG. 23 is a left side elevational view; and

FIG. 24 is a rear elevational view thereof.
